APPARATUS FOR MAKING ARTIFICIAL
SILK

Joseph Lyall Hutchings, Newark, N. J., assignor
to Brosites Machine Company, Inc., New York,
N. Y., a corporation of New York

Application May 11, 1938, Serial No. 207,359

2 Claims. (Cl. 18-8)

This invention relates to apparatus for and methods of manufacturing artificial thread, for instance rayon or artificial silk, and particularly to methods of and apparatus for treating tubular packages or cakes formed of artificial thread in what is known as a spinning pot.

In the manufacture of rayon a viscose solution is pumped through spinnerettes, congealing as it passes through a coagulating bath, then 10 passing over a godet or godets and is conducted into the entrance end of a spinning pot funnel, the opposite end of this funnel having an opening disposed on the axis of the spinning pot or bucket, which pot or bucket is rotated at high 15 velocity. The thread passing through the spinning pot funnel is thrown outwardly after leaving the funnel against the inside wall of the rapidly rotating spinning pot, owing to the action of centrifugal forces, the thread being given 20 at the same time the desired twist. The funnel through which the thread is passed has an oscillating motion in a vertical path and this motion is controlled so as to cause the thread to be disposed uniformly over the inside surface 25 of the spinning bucket. Gradually a tubular package or winding of thread is thus built up within the bucket, this package being generally designated in the art a spun yarn cake.

After the cake has been completed 30 it is removed from the spinning bucket and is ready for further treatment. The completed cake, ready for such further treatment, has a wall thickness of approximately three-fourths of an inch and has the general appearance of 35 the frustum of a hollow cone. Before the spun yarn cake is subjected to any further treatment, such as washing, bleaching, dissulphuring, etc. for the removal of various salts and acids which it may contain, it is generally wrapped with a 40 fabric member or an elastic fabric stocking to protect it from abrasion in further handling. The cake as thus wrapped is then placed in an apparatus for performing the operations of 45 washing, bleaching, dissulphuring and soaping. After having been washed it is sometimes subjected to a hydroextracting operation to remove 50 excess liquid, prior to being subjected to the final drying operation. In the drying operation the thread tends to shrink and unless protection is made to relieve the tension in the thread prior to placing the cake in the drier, a serious difficulty is met with in that the yarn from the inside of the spun cake does not color as uniformly as that upon the outside of the 55 cake. This inequality in covering during the

dyeing operation is attributed to the fact that the yarn at the inside of a spun cake is free to shrink, without being unduly tensioned, whereas as the outside strands are placed under considerable tension in the process of drying, these 5 strands being supported by the strands directly beneath them while drying and hence being prevented from contracting. It is believed that the excessive tension to which the outermost strands of the cake are subjected causes the 10 formation of hard spots in these strands or filaments which in turn results in non-uniform dyeing.

Various means for and methods of dealing with this difficulty have heretofore been designed 15 or suggested. It has been suggested for instance that by deforming the cake by the application of mechanical means applied radially thereto, so as to form a number of spaced indentations extending inwardly, the outer strands or convolutions of thread will be provided with a sufficient amount of "slack" to prevent excessive tensioning due to shrinkage upon drying. The purpose of the present invention is to provide an improved method of and apparatus for treating 20 25 30 35 40 45 50 55 60 65 70 75 80 85 90 95 100 cakes or packages of artificial thread in such manner as to provide the necessary "slack" in the outer convolutions but without deforming the cake in a substantial manner as heretofore, the cake retaining substantially its smooth, frustoconical inner and outer surfaces. The apparatus and method comprising the present invention likewise are useful in the formation of a spun yarn cake in which the threads are "crinkled" or serpentine in form, which configuration of thread is highly desired for certain purposes. Every convolution or strand of a cake of thread subjected to the operation of the apparatus is crinkled uniformly throughout its length and enough slack produced in every increment of length to enable the thread to shrink when dried without being tensioned.

A further advantage of the invention resides in the fact that hydroextraction is or may be accomplished at the same time that the thread 45 is crinkled and provided with slack. If it be preferred, however, to employ the centrifugal method of hydroextraction, the method used in placing the slack in the strand of the yarn cake automatically reduces the cake in diameter so 50 that it may be readily placed in the smaller diameter hydroextracting bucket and the operation of hydroextraction carried on in the centrifugal manner.

The apparatus employed in the practice of the 55

improved method is of the simplest character. It comprises essentially a tubular mandrel having a diameter slightly less in length than the inner diameter of the tubular cake which is to be contracted, together with fluid pressure actuated means for acting on and contracting the cake so that it closely engages the mandrel. This means may be caused to function either by creating a greater than atmospheric pressure against one side, or a sub-atmospheric pressure against the other side thereof. In the first case means is provided for supplying a pressure chamber with a fluid under pressure and when such fluid is introduced it deflects a flexible inner wall of the chamber radially inward toward the mandrel so that this flexible wall contacts with and bears against all areas of the outer surface of the yarn cake interposed between the mandrel and chamber. The pressure may be increased at the will 10 of the operator to any desired extent and a pressure is employed which is sufficiently great to cause the diametric contraction of the cake, the inner diameter of the cake being shortened until the inner surface thereof lies snugly against the 15 surface of the mandrel. During this operation all thread convolutions of the cake are contracted circumferentially and all individual convolutions are "crinkled" or rendered serpentine in configuration, for the purpose specified. In the second case a vacuum pump may be employed to 20 create a sub-atmospheric pressure within the mandrel, which causes said means to move in its cake compressing direction.

Two embodiments of the apparatus are illustrated in the accompanying drawings by way of example but it will be appreciated that further variation in design and construction of the component elements of this apparatus may be freely made without departure from the invention.

40 In the drawings:

Figure 1 is a section through the axis of the mandrel used with one form of the apparatus and also through the axis of the encircling pressure chamber, these two members being coaxial, showing a cake positioned to be acted upon intermediate the mandrel and pressure chamber;

Figure 2 is a similar view showing the movable wall of the pressure chamber, and the work or spun yarn cake, in the positions which they occupy at the conclusion of the compressing operation;

Figure 3 is a section on line 3—3 of Figure 1;

Figure 4 is a perspective view of a spun yarn cake, portion of the fabric wrapping being broken away to disclose the outer convolutions or windings of thread;

Figure 5 shows in elevation portions of certain surface convolutions of a thread or yarn cake before the cake is subjected to the compression operation;

Figure 6 is a similar view showing these convolutions after the cake has been compressed in the specified manner;

Figure 7 is a section similar to that of Figure 1, taken axially through an apparatus of the suction type; and

Figure 8 is a section on line 8—8 of Figure 7.

The apparatus comprises essentially a suitably supported base which is indicated at 10 in the drawings and which may conveniently be in the form of a disc having a central hub 10' provided with an aperture for the reception of sliding rod 11. The pressure chamber may conveniently be annular as shown and in the form of the chamber illustrated comprises an outer cylindrical wall

12 having horizontal flanges 12' and 12" extending inwardly, so that the wall 12 may be said to be channel-shaped in vertical cross-section, and a flexible inner wall 13 which is in the nature of a diaphragm, being preferably formed of gum rubber. The flexible wall 13 is tubular and its upper end extends outwardly over the annular flange 12", being retained between that flange and a clamping ring 14, this ring being secured to flange 12" by means of screws such as indicated at 15. The lower margin of the flexible wall 13 likewise extends outwardly and is retained between the upper surface of the base 10 and the annular lower flange 12' of the pressure chamber wall 12, flange 12' being secured to base 15 by screw bolt 16.

Secured to the upper end of the vertically slideable rod 11, at a point above the base 10, is a disc 20, the periphery of this disc being grooved on its underside to receive an annular shoulder 10" integral with and projecting upwardly from the base. Shoulder 10" likewise comprises means for definitely locating the pressure chamber 12 coaxially with the base 10, when the parts are being assembled. The mandrel is indicated at 21 and is seen to comprise a tubular member disposed coaxially with the base and with the pressure chamber, this mandrel having a peripheral flange at its upper end, portion of which lies in the plane with the flange 12" of the pressure chamber, and portion of which overhangs the pressure chamber so that, by means of rods 22, which pass through aligned apertures in the outer margin of the base 10 and the outer margin of this mandrel flange, and wing nuts 23, the mandrel may be rigidly but detachably secured to the base.

It will be perceived that the outer surface of the tubular portion of the mandrel tapers downwardly and that the inner surface of the flexible wall 13 of the pressure chamber is correspondingly tapered. In the space intermediate the mandrel 21 and the flexible wall 13 may be positioned the spun yarn cake, generally indicated at C, this cake having its annular lower edge surface resting upon the plate or disc 20 and its upper annular end surface lying quite close to, even actually in contact with, the undersurface of the mandrel flange which is disposed directly above it. It will be perceived that the cake C is in the form of a hollow frustum of a cone and that its inner and outer frustoconical surface have the same angularity as those of the mandrel and inner wall of the pressure chamber. A conduit or pipe for introducing fluid into the pressure chamber is indicated at 25 and a fluid escape conduit at 26, conduit 25 being provided with a control valve 27 and conduit 26 with a control valve 28. The mandrel has formed therein a plurality of radially extending apertures 30 to permit liquid expressed from the cake C to pass into the interior of the mandrel and the disc 20 is provided with one or more apertures 31 to permit such extracted liquid to pass through this disc and onto the upper surface of the base member 10. The base member 10 likewise has one or more apertures 32 extending vertically thereto through which liquid collected on the upper surface of the base may pass to the offtake pipe 33. A pressure gauge is indicated at 34, this gauge being in communication with the interior of the pressure chamber and indicating at all times the pressure which exists in this chamber.

After the various parts are assembled in the positions in which they are shown in Figures 1

and 3, with a cake C intermediate the mandrel and the flexible wall 13, the valves 27 and 28 may be opened and water or other fluid allowed to flow into the pressure chamber. After the chamber has been filled valve 28 is closed to prevent further escape of liquid but valve 27 allowed to remain open to admit further quantities of liquid under the desired pressure. This pressure acts upon the movable wall 13 of the pressure chamber 10 and deflects this wall inwardly into contact with the outer surface of the tubular cake C. Continued application of the pressure in sufficient amount causes the wall 13 to exert sufficient pressure upon the outer surface of the cake C to 15 radially and circumferentially contract this cake, the pressure being maintained until the inner wall of the cake is in full contact with the outer surface of the mandrel 21. Such moisture as is 20 expelled from the cake during the application of this pressure will flow through apertures 30 in the mandrel and escape in the manner previously described.

After the cake has been fully compressed the valve 27 may be closed and valve 28 opened, thus 25 permitting the fluid within the pressure chamber to escape to a certain extent and the flexible wall 13 to resume the position in which it is shown in Figure 1. The wing nuts 23 may then be loosened and the mandrel 21 lifted and placed to one side. 30 Thereafter the rod 21 and disc 20 may be lifted, elevating the cake C into such position that it may readily be grasped by the operator. A fresh cake may be placed on the disc 20, the mandrel replaced, and the operation repeated.

35 Prior to this diametrical and circumferential compression of the cake C its threads have the appearance of those shown in Figure 5, whereas after the compression operation has been carried out, these threads will have somewhat the appearance of those shown in Figure 6, being longitudinally compressed and "crinkled" or rendered serpentine, the advantages of which thread formation have been heretofore described.

The embodiment of the apparatus shown in 45 Figures 7 and 8 includes the major features of the apparatus illustrated in Figures 1 to 3 inclusive, but here the movement of the cake compressing member or rubber diaphragm 40 is brought about by reducing the pressure within the mandrel 41 instead of increasing the pressure on the outside of the diaphragm as before. It will be perceived that the hollow tubular portion of the mandrel is closed by the web 41' and that the diaphragm supporting member 42 is provided with openings 42' so that the outer surface of the diaphragm is always subjected to atmospheric pressure. The mandrel wall is perforated as before and the disc 43 is likewise perforated, as at 43'. An aperture 44' in base 44 is in communication with a conduit 55 having a branch 56 leading to a water separator and vacuum pump and a branch 57 leading

to the atmosphere, these branches being controlled by valves 56' and 57' respectively. By closing valve 57' and opening valve 56' a sub-atmospheric pressure may be established within the mandrel and within the diaphragm 40 so 5 that the cake is compressed on the mandrel by inward movement of the diaphragm 40 under the external pressure of the atmosphere. A pressure gauge is indicated at 60 and a packing around rod 61 is indicated at 62, this packing preventing 10 leakage of air into the mandrel.

After the cake has been compressed the valve 56' may be closed and valve 57' opened, thus 15 re-establishing atmospheric pressure within the mandrel and permitting the diaphragm to resume its original position. The compressed cake may then be removed as before. When this form of apparatus is employed a substantial proportion of the moisture content of the cake may be withdrawn without exerting an unduly high mechanical pressure upon its outer strands or convolutions, which is undesirable, and the degree of moisture extraction may be such as to make unnecessary further water extracting operations, such as an extraction by the centrifugal method, 25 thus simplifying the process as a whole and lowering the cost. The extracted water or other liquid is of course withdrawn from the cake through the apertures in the mandrel and passes downwardly through pipe 56 to a water and gas 30 separating device.

If desired the cake to be treated may be subjected to internal suction and positive external pressure simultaneously by applying a greater than atmospheric fluid pressure to the outside of 35 the diaphragm and establishing a sub-atmospheric pressure within the diaphragm and mandrel. The fluid used in creating a pressure upon the outside of the diaphragm may be either a liquid, such as water, or a gas, such as air. Obviously the details of design of the various elements of the apparatus may be considerably modified without departure from the invention.

Having thus described the invention, what is claimed as new and desired to be secured by Letters Patent is:

1. Apparatus for use in the manufacture of artificial thread including a tubular mandrel, and a pressure chamber encircling the mandrel, the inner wall of the pressure chamber being spaced 50 from the mandrel surface to permit introduction of a tubular thread cake between said wall and the mandrel, said wall comprising a flexible diaphragm adapted to engage all surfaces of the cake when deflected inwardly by increase in pressure in 55 said chamber.

2. The combination set forth in claim 1 in which the inner wall of said chamber comprises a tubular member of rubber.

JOSEPH LYALL HUTCHINGS.
